UNITED STATES PATENT OFFICE.

JOHN S. CUREZON, OF STORES, UTAH.

PICK-HANDLE PROTECTOR.

Application filed June 24, 1922. Serial No. 570,606.

To all whom it may concern:

Be it known that I, JOHN S. CUREZON, a citizen of the United States, residing at Storrs, in the county of Carbon and State 5 of Utah, have invented certain new and useful Improvements in Pick-Handle Protectors, of which the following is a specification.

My invention relates to guards or protectors 10 for tool handles and these protectors are more particularly intended for pick handles such as coal miners use.

The cost of furnishing and replacing wooden handles of picks constitutes a considerable item in coal mining, as the handles are exposed to injury from rocks and sharp lumps of coal during operation, and the handles are particularly subjected to such injury close under the head of the pick. 20 They are also liable to be burnt during the process of retempering the pick points, unless special precautions are taken to protect them.

The main object of the invention is to 25 furnish the miner with an effective guard for his pick handles, at a very low cost, and another object is to make the guard adjustable to handles of different sizes and also to make it easily attachable on any handle.

It will be evident that a protector of this 30 kind is also useful for handles of other tools, such as axes, hammers, sledges, and the like.

In the accompanying drawing one embodiment of the invention is illustrated.

Figure 1 is a perspective view of a pick 35 with my protector attached to the handle;

Fig. 2 is a transverse section along line 2-2 of Fig. 1, and

Fig. 3 is the blank or plate used to manufacture the protector.

In the drawing the reference numeral 10 represents the handle and numeral 11 the head of an ordinary pick. The handle 10 has generally an oval cross section near the head 11, as best seen in Fig. 2, and the protector is made to closely fit around this portion of the handle and extend upwardly thereon for some distance.

The protector consists of two members 12 40 and 13, each having an elongated body 14

and a pair of medially positioned wings 15 extending from the body 14. The wings are furnished with a row of perforations 16 and one end of the body, as at 17, may be slightly wider than the opposite end, as at 18; this for the purpose of fitting the different diameters of the handle which is generally tapered.

The protector is preferably manufactured by stamping out blanks of the shape illustrated in Fig. 3 of sheet metal or heavy tin and either furnished flat, as seen in the said figure, or curved along a longitudinal axis to conform with the configuration of the handle, as seen in Fig. 2. The two body members 12 and 13 of the protector are slipped over the heavy portion of the handle as seen in Figs. 1 and 2, and made to embrace the latter. In this position the wings 15 of one body member 13 will overlap the 55 wings from the mating body member 12 and the perforations 16 in the wings will coincide with each other to receive a brad or screw 19 on each side of the handle for fastening the protector thereon and securing the two body members 12 and 13 rigidly together at the same time.

It will be evident that by furnishing a plurality of perforations 16 in each wing it is possible to enlarge or contract the protector to suit any handle.

It will also be noted that the material used is flexible enough to permit the opening or closing of each body member to fit over its particular half of the handle.

A pick furnished with a protector of this character does not need a renewal of the handle for some time as any blows from rocks or lumps of coal will not hit the handle directly but will be received by the protector which in this manner saves the handle.

When putting the pick in the fire for tempering the points the flame will in this case not burn the handle as the flame will strike the protector instead of the handle.

Having thus described the invention, what is claimed as new is:

An adjustable tool handle protector comprising a pair of mating members of hard fireproof material, each member having a 100

rectangular body and a pair of medial wings making the member symmetrical as regards its longitudinal and transverse axes, each wing provided with a series of perforations, 5 the body being folded to conform with a portion of the transverse configuration of the handle, while said wings are adapted to overlap on the opposite sides of the handle,

and said perforations selectively register in corresponding wings in accordance with the 10 cross section of the handle, and fastening devices inserted through the registering perforations in said wings for securing said members to each other and to the handle.

In testimony whereof I affix my signature.
JOHN S. CURZON. [L. s.]
